APPARATUS FOR SEALING CONTAINERS

Robert J. Stewart, Baltimore, Md., assignor to
Crown Cork & Seal Company, Inc., Baltimore,
Md., a corporation of New York

Application August 16, 1938, Serial No. 225,230

7 Claims. (Cl. 226—82)

The present invention relates to an apparatus for sealing containers and, more particularly, to an apparatus whereby steam is placed in the head space of the container so that, by subsequent condensation, a vacuum will be provided in the container head space.

Apparatus heretofore provided for placing steam within the head space of containers so that a vacuum will subsequently be established within such head space have not been altogether satisfactory because of the fact that upon condensation of the steam, some moisture has been present in the container head space. With many products, particularly food products, such moisture is highly objectionable and the use of such prior apparatus has therefore been limited to the packing of products which will not be damaged by moisture. It is found that the reason for moisture within the head space of a container after condensation of the steam has been due to the fact that too great a quantity of steam has been injected into the container head space. Only a given amount of steam at a given pressure is required in a head space to provide a sufficient vacuum and, naturally, if too much steam is placed within the head space, surplus potential moisture is present and, when the steam condenses, free moisture will be present in the head space.

In apparatus wherein steam is forcibly injected into the head space, particularly when the container is cold, some condensation will immediately occur unless conditions are very carefully and constantly regulated. That is, free moisture can be avoided by carefully regulating the steam so that it will be in an extremely dry state, but this requires continuous adjustment of the machine due to the fact that steam which will be dry when a plant is at a high temperature, will be less dry if the plant temperature drops very slightly and temperature regulation in the type of large buildings used for packing is a rather difficult matter. Such buildings, with high ceilings, are also subject to interior drafts, and drafts within a plant and moving through the steam chamber will also affect the dryness of the steam. It is also a fact that the projection of a jet of steam under force in the steam chamber induces a draft through the steam chamber with the result that a quiet body of steam cannot be maintained in the steam chamber to pre-heat cold containers prior to the jetting of steam into their head spaces. Aside from the above factors, prior machines wherein steam is injected directly into

the head space of the containers are rather complicated in construction due to the fact that an injecting means adjustable as to height must be provided.

5 The principal object of the present invention is to provide an apparatus for vacuumizing containers which is extremely efficient and of simple construction.

Among other features of the present invention 10 which contribute to the attainment of the above object is the fact that steam is placed in the head space of an open container simply by movement of the container through a steam atmosphere rather than by injection of the 15 steam into the head space.

A further object of the invention is to provide a novel form of steam chamber for use in a container vacuumizing apparatus, the steam chamber being particularly designed to insure 20 that a body of steam in a quiet state will be evenly distributed throughout at least the upper portion of the chamber and a draft through the chamber will not be induced.

Another object of the invention is to provide 25 a steam chamber of such arrangement that the steam within the same will be maintained in a dry state without the necessity of continuous and careful adjustment of the steam supply.

In apparatus of the type described above, it 30 is necessary to apply a cap loosely to a container while the latter is standing upon a moving conveyor belt. Mechanisms heretofore provided for this purpose have not been satisfactory due to the fact that the cap release means of 35 the cap delivery chute had to be sufficiently braced, by a spring or the like, to resist the weight of a line of caps in the chute and, at the same time, the cap release means had to operate sufficiently freely to permit a container 40 to remove a cap from the chute by contact with the cap release means. Where the release means is not so designed that it will readily release the lowermost cap when the container contacts with the same, the container will fall over backwards, thereby interfering with the 45 operation of the machine as well as wasting the contents of the container.

A further object of the invention is to provide 50 a means for loosely positioning caps upon moving containers without the danger of causing the containers to be tilted backwardly by contact with the cap applying means.

Another object of the invention is to provide a capping mechanism particularly designed for sealing caps to moving containers.

In sealing a cap to a container moving beneath a capping mechanism, it is necessary that the contact of the capping head with the container does not arrest the forward motion of the container with the conveyor, otherwise the container will be tilted backwardly. Even if such backward tilting does not cause the container to be upset, nevertheless, if the container is tilted only slightly backwardly at the moment it moves out of contact with the capping head, the cap may be positioned at an angle on the mouth of the container. Obviously, if a cap is not applied squarely to the mouth of the container, a proper seal will not be provided.

Various capping mechanisms have heretofore been provided for the purpose of insuring that a cap will be applied to a container without interruption of the forward motion of the container, but such mechanisms have not overcome the difficulties involved, due to the fact that the capping means has moved downwardly toward the container, as well as upwardly away from the container along lines too sharply at an angle to the direction of container movement. The use of rotary members of fairly large diameter for this purpose has also been proposed but the practical difficulty with such devices has been that the initial contact of the roller is naturally only a contact with the leading portion of the container cap, while the final contact of the capping element is only with the trailing portion of the cap. During either of such contacts, the cap may be tilted with respect to the container and such final contact, in particular, is apt to prevent an efficient sealing of the cap upon the container.

Still another object of the present invention is to provide a capping mechanism for moving containers which is of such design that it will bear upon the full area of the cap during the entire time that it is in contact with the latter.

Other objects and advantages of the invention will be apparent from the following specification and drawings, wherein:

Figure 1 is a side elevation of the steam chamber and capping mechanism forming part of the apparatus of the present invention.

General description of construction and operation

The construction and operation of the appa-

ratus of the present invention, and the method of vacuumizing containers performed by the apparatus may be generally described as follows:

Referring to Figure 1, the containers J move into the steam chamber 18 on the conveyor 15. Chamber 18 is supplied with steam at suitable pressure through a steam supply line, and, as hereinafter described, the chamber is of such construction that the steam will be quietly distributed throughout the chamber so that no drafts will be created in the chamber. This will result in the chamber being kept filled by a cloud-like and stationary body of steam. During passage of a container through the body of steam in the chamber 18, the head space of the container will become filled with steam and a rarefied atmosphere will thus be provided in the head space.

When the containers have moved from the steam chamber 18, a cap C will be loosely applied to each container by the cap applying mechanism generally indicated by the numeral 19. In this way the steam which has filled the head space of the container will be kept in the head space of the container. The container J with cap C loosely applied thereto will then move under the capping mechanism 20 which will force the loosely applied cap C down upon the container mouth to securely seal the container. The capping mechanism, operating in the open atmosphere, will also serve to immediately cool the cap C and the upper portion of the container so that the heated and rarefied atmosphere within the head space of the container will be condensed or contracted, thereby establishing a vacuum condition within the head space of the container before the latter leaves the capping mechanism 20.

The delivery of the containers to conveyor 15 may be controlled by a timing and centering mechanism such as disclosed in my application for Article timing devices, Serial No. 428,797 filed January 29, 1942, which is a division of the present case.

The operation of each of the mechanisms of the apparatus is hereinafter described in more detail in connection with the description of the construction of each mechanism.

The steam chamber

As generally indicated in Figure 1, the steam chamber 18 is in the form of a hood which surrounds and extends above the container supporting conveyor 15 so that containers J moving with the conveyor 15 will be maintained in a steam atmosphere while moving through the chamber.

Referring to Figure 2, which shows the steam chamber in transverse cross section, and to Figure 5, which shows the chamber in longitudinal vertical cross section, the chamber comprises an inner wall structure 108 including side walls 101 and 102 and a bottom wall 103. The walls 101 to 103 may be welded together so as to be of substantially U-shaped form. The side walls 101 and 102 have blocks 104 welded to their outer surfaces which blocks are fixed to the upper ends of tubular slides vertically movable in the base 108 of the mechanism as generally indicated in Figure 2 and as hereinafter described in detail. It will be observed that the upper edges of the walls 101 and 102 will be positioned at such height with respect to the upper run of the supporting conveyor 15 that the upper portion of a container J on the conveyor will be adjacent a U-shaped screen 105, preferably of wire mesh, which extends between the upper edges of the

side walls 101 and 102. Screen 108 extends from the inlet end of the steam chamber 18 to a point adjacent the cap applying mechanism 19 as best shown in Figure 5. A steam inlet or expansion chamber 110 is provided above the screen 108, chamber 110 being of greater width than the inner wall structure and screen 108 to provide inlet portions 111. Steam inlet pipes 112 open to the lower walls of the inlet portions 111 so that steam issuing from steam inlet pipes 112 will not blow directly toward the screen 108 but will jet or discharge against the upper wall of chamber 110, which wall thereby serves as a baffle to break the force of the steam. The pipes 112 extend downwardly through the tubular vertical guides 105 to communicate with a source of steam as hereinafter described.

The inlet end of chamber 18 is provided with an end wall 115 (Figures 4 and 5) having a cut-out 116 therein through which containers may move into the steam chamber on the conveyor 15, the wall 115 also closing the adjacent end of the steam inlet chamber 110. The opposite end of the steam inlet chamber 110 is closed by a plate 118, having its lower surface of arched form so that the adjacent end of the screen 108 may be fixed thereto. As best shown in Figures 3 and 4, plate 118 has an aperture 119 at one side thereof so that steam entering the inlet portion 111 on that side of the steam chamber 110 may move through the aperture 119 and into a chamber 120 (Figure 4) on the opposite side of plate 118 and extending alongside the path of travel of containers. Chamber 120 has its wall adjacent the containers formed of a mesh screen 121 of material similar to that used in the screen 108. The lower end of the cap applying mechanism 19 is positioned opposite the screen 121 referred to above, though, as hereinafter described, caps will not be delivered to the containers until after they have left the steam chamber 18.

It will be generally observed that by the above construction, the portion of chamber 18 adjacent inlet 116 and also the major portion of the length of the steam chamber 18 will be maintained filled with a quiet cloud of steam at low pressure because the steam enters the chamber through the mesh screen 108 which further breaks the force of the steam, and that just prior to leaving the chamber 18, the containers will move through a steam atmosphere provided by the lateral steam chamber 120 at the outlet end of the steam chamber.

In order to prevent steam within the space defined by the inner wall structure 100 from condensing, and in order to maintain the steam in a dry state, electric heating elements 125 are secured to the outer surfaces of the side walls 101 and 102, these heating elements being positioned near the upper portions of such walls and preferably extending the entire length thereof. It will also be noted that the bottom wall 103 of the inner wall structure 100 is depressed at its central portion so that any condensation which may form upon the lower portions of the side walls, as when the flow of steam is cut off, will flow to the depressed portion and along the same to the end of the wall and leave the steam chamber at that point. The lower wall 103 preferably does not extend the entire length of the steam chamber, but is cut away at the outlet end thereof as illustrated in Figure 5.

The steam chamber is covered with heat-in-

sulating material, not shown, to further prevent condensation.

As best shown in Figure 2, one of the tubular slides 105 which supports the steam chamber extends down through an apertured boss 130 on the upper surface of the base 106. The other tubular slide 105 extends down through a collar 131 fixed to the upper wall of the base by means of screws 132 or the like. Collar 131 has a sleeve or short hollow shaft 133 rotatable thereon, sleeve 133 being provided with gear teeth 134 adapted to mesh with a pinion 135 journaled in the central portion of the upper wall of the base 106 as indicated at 136. The pinion 135 is provided with a hub 137 having its bore threaded to engage a threaded rod 138. The upper end of rod 138 carries a cross frame 139 to which the tubular guides 105 may be welded or otherwise secured. Rod 138 is fixed against rotation in the frame 139 and it thereby follows that rotation of collar 133, by means of a hand wheel 140 provided at the upper end of the same, will cause the rod 138 and frame 139, as well as the entire steam chamber carried by the tubular guides 105, to be raised or lowered.

The steam supply pipes 112 which extend down through the tubular guides 105 have drain fittings 143 at their lower ends and, above the drain fittings, have flexible steam lines 144 connected thereto as shown in Figure 1. The flexible lines 144 are in turn connected to a pressure reducing valve 145 suitably mounted in the base 106 of the apparatus. The provision of the flexible lines 144 of course permits the supply lines 112 to be moved vertically with respect to the base. The pressure reduction valve 145 is suitably connected to a source of steam.

In operation, when a filled and open container J moves into the steam chamber 18, the air in the head space of the container will be displaced by steam, partly due to the fact that the air will be heated by the surrounding steam and will therefore rise from the head space. Displacement of air also occurs because the atmosphere in the steam chamber is rarefied by reason of the presence of the steam in the chamber. Thus, when a container moves from the steam chamber, its head space will be filled with steam, and the loose positioning of a container cap or closure on the container by the cap applying means will cause this steam to be retained in the head space.

The provision of the steam chamber extension 120 at the outlet end of the chamber serves to maintain steam at such end of the chamber and prevents too much steam from being withdrawn from the main chamber by eddy currents induced by the movement of containers out of the main chamber. The use of an auxiliary chamber at only one side of the path of movement of the containers is found to be particularly efficient in preventing such eddy currents.

The cap applying mechanism

The cap applying mechanism 19 is so arranged with respect to the steam chamber 18 that a cap will be positioned upon each container just after the latter leaves the steam atmosphere of the steam chamber 18, the cap applying mechanism comprising a tray 150 (Figure 1) and supported upon a post 151 projecting upwardly from the steam chamber 18. The tray 150 is positioned in a horizontal plane and an operator may place caps upon the tray with their top walls uppermost and with the depending skirt of the cap extending downwardly, the caps then being moved

by hand toward the outfeed arm 152 of the tray. A cap chute 153 having a channel therein of proper cross section extends downwardly from the outfeed arm 152, chute 153 extending through an opening 154 (Figure 5) in a closure plate 155 which forms part of an upward extension 156 of the steam chamber 18. The upward extension 156 is preferably pivoted on steam chamber 18 so that the lower portion of the chute within the steam chamber will be accessible to the operator. As is best shown in Figures 3 and 7, the chute 153 is laterally inclined so that while its upper end is offset with respect to the longitudinal center line of the container supporting conveyor 15, its lower end will be centered with respect to such center line. Nevertheless, as indicated from the Figure 3 sectional view of the chute, any transverse line through the upper or lower wall of the chute will lie in a horizontal plane.

One corner of the lower end of the chute is cut away as indicated at 159 in Figure 7 so that the edge of this wall will be transverse to the longitudinal center line of the conveyor 15. A pair of stop devices 160 are so mounted upon the chute that they will normally lie in a plane transverse to the center line of the conveyor and therefore transverse to the line of movement of containers J upon the conveyor. More specifically, each plate 160 includes an arm 161 pivoted between the upper and lower walls of the chute as indicated at 162, the upper portion 163 of the free end of each plate 161 extending directly downwardly in a vertical plane, while the lower portion 164 of each plate is inclined outwardly. A spring 165 extending between depending pins 166 on the plates normally holds the latter toward each other, this spring being sufficiently strong to hold the plates in this position against the weight of the caps within the chute, but permitting the plates 160 to be readily spread apart by the movement of the mouth of the container beneath the same. In other words, when a container moves toward and between the extreme ends of the plates 160 as indicated in Figure 6, the plates will freely open, due to the marked leverage exerted by the containers acting upon the ends of the plates. The leading wall of the container mouth will simultaneously contact with the lowermost portion of the cap skirt to draw the cap out of the chute between the plates 160, the angle at which the plates are arranged with respect to each other serving to center the cap skirt with respect to the container mouth.

A cap leveling arm 168 is pivoted to a lug 169 on the top wall of the cap chute by means of a pin indicated at 170. The free end portion 171 of arm 168 is bent upwardly and is maintained in a substantially horizontal plane as indicated in Figure 6 by an adjustable set screw 172 extending through the arm 168. The bend 173 in the arm 168 is so arranged that a cap may move freely out of chute 153 and along a path in alignment with the bore of such chute and without contacting with the arm 168. However, just as the trailing portion of the cap skirt drops from the lower wall of the chute 153, its upper wall will come into contact with the bend 173 of the arm 168 by reason of the further forward movement of the container, and the continuing forward movement of the container will cause the cap to be brushed beneath the normally horizontal portion 171 of arm 168 so that the cap will be properly positioned upon the mouth of the container, that is, with its top wall in a substantially hori-

zontal plane. The contact of the angle or bend 173 of arm 168 with the trailing upper portion of the cap just at the moment that this portion of the cap is dropping from the chute will further insure that the trailing portion of the cap will be forced downwardly to lie in a horizontal position upon the container mouth. Thus, the cap will be in a proper position for presentation to a capping device and so that the latter may readily force the cap to sealed position upon the mouth of the container.

In order that caps moving downwardly in the chute 153 will be urged to a position centered between the stop plates 160, a guide plate 178 is mounted at the lower end of the side wall 153a of the chute which is substantially opposite these stop plates. Guide plate 178 has a stem portion 179 which extends through an aperture in the side wall 153a of the chute so that the guide plate 178 may be moved to such position within the chute as to urge small caps toward the opposite side wall of the chute and thus to a centered position with respect to the stop plates 160. As shown in Fig. 7, the lower end of guide plate 178 is angled inwardly as at 178a so as to further direct caps to a centered position with respect to the stop plates 160. A set screw 180 threaded in the upper wall of the chute engages the stem 179 to hold the guide plate in adjusted position. Also, to eliminate friction, the bottom wall of the cap chute 153 may be provided with spaced and upstanding ribs 181.

The capping mechanism

The capping mechanism 20 shown in Figures 8 to 11 comprises a casing 185 supported from a standard 186 by an upper link 187 (Figures 1 and 8) and by two lower links 188 and 189. The link 187 is parallel with the lower links 188 and 189 so that a supporting structure of parallelogram form is thus provided. As indicated in the drawings, the links extend generally horizontal. Link 187 is pivotally connected to the extreme upper end of the standard 186 by a pin 190, the pin extending through the link and also through two arms 191 at the upper end of the standard 186. Link 187 extends into the upper central portion of the casing 185 and is pivoted to the casing by a pin 192 which extends through the walls of the casing as shown in Figure 10, each end of the pin extending into a swivel or collar 193 threaded upon a rotatable rod 194 having its lower end fixed to the base frame 195 which supports the container conveyor 15. The links 188 and 189 are connected to the standard 186 by means of a shaft 197 (Figures 8 to 11) which extends through the links and also through the standard. It will be observed that link 188 is connected to one side of the standard 186 while link 189 is connected to the other side of the standard. These two links are joined to opposite sides of the casing 185 by stub pins 198 which extend into the corresponding sides of the housing as shown in Figure 10. The base frame 195 supports the upper run of conveyor 15 during the travel of the latter beneath the capping mechanism and the lower ends of the supporting and adjusting rods 198 are rotatably journaled in this base frame 195. The rods 194 are provided with sprocket wheels 199 at their lower ends beneath the base frame and a sprocket chain 200 extends about the sprocket wheels. The upper end of each rod 194 carries a hand crank 201. Rotation of either hand crank will thus cause both rods 194 to be rotated and since the swivel sleeves 193 are held against rota-

tion, these sleeves will be moved either upwardly or downwardly to adjust the position of the casing 185 and the capping head carried thereby with respect to the upper run of the container supporting conveyor 15. The upper link 187 and the two lower links 188 and 189 will of course swing either upwardly or downwardly to permit this movement, the links retaining their parallel relation.

The capping device comprises a housing 205 provided with a central chamber 206 on which is mounted the capping disc 207, the housing 205 also being provided with a longitudinally extending plate 208 (Fig. 8) on each end thereof. Each plate 208 has a relatively large aperture 209 therein which fits about a rotating eccentric 210. Thus, the plates 208 serve as eccentric straps whereby the housing 205 is moved to an elliptical orbit and in a vertical plane. Each eccentric 210 is formed integral with or fixed to a hollow shaft 211 which rotates about a pin 212 journalled at its ends in the side walls of the casing 185. Each shaft 211 has a pinion 213 mounted concentrically thereof and, as indicated in Figure 8, the two pinions mesh with a pinion 214 fixed to the shaft 198. Shaft 198 also has one or more sprocket wheels 216 fixed thereto within the supporting link 188. Sprocket chains 217 extend about the sprocket wheels 216 and are driven from sprocket wheels 218 rotatable on the pin 197 which extends through standard 186.

Referring to Figure 11, the collar which carries the sprocket wheels 218 also has two other sprocket wheels 220 formed thereon driven by sprocket chains 221 extending up through the standard 186, these latter sprocket chains being driven by a motor 223 mounted below the base 195 of the capping mechanism. A take-up idler 224 may be provided beneath the sprocket chains 217 as indicated in dotted lines in Figure 8.

The chamber 206 of housing 205 has a plunger element 230 slidably mounted therein, plunger 230 normally being held against the removable bottom plate 231 of the chamber by a spring 232 as shown in Figures 8 and 10. The upper end of the spring 232 bears against a plate 234 which is held downwardly and under tension by a set screw 235 extending through the upper end of the chamber to permit the tension of the spring to be adjusted. Plunger 230 has an extension 240 which projects through an aperture in the bottom plate 231 of the housing and the capping head or plate 207 is fixed to this extension of the plunger by releasable means.

By the above arrangement, rotation of the eccentrics 210 will cause the housing 205 to be moved through an elliptical path within the casing 185, and the capping plate 207 will of course have a corresponding movement. As indicated by the various dotted line positions of the capping head illustrated in Figure 8, in moving downwardly toward a container J upon the container supporting conveyor 15, the capping plate 207 will be moving in the same direction as the container. When the capping plate 207 contacts with the cap C upon the container J, the spring 232 will hold the capping plate downwardly under sufficient pressure to force the cap to sealed position upon the container. In moving upwardly from the cap C, the plate 207 will also be moving generally in the same direction that the container moves with the conveyor 15. In other words, the orbital movement of the capping plate along an elliptical path will minimize the possibility of the container being tilted upon the conveyor when the capping plate 207 contacts therewith, and

since the lower face of the capping plate will be lying in a horizontal plane throughout its movement, it will have no tendency to tilt a cap C with respect to the container mouth as it leaves the container.

The design of the eccentrics 210 is preferably such that the upper and lower portions of the elliptical path through which the capping plate 207 moves will be relatively flat so that the capping plate may be in contact with a cap C for an appreciable time, rather than merely having a point contact with the cap. This result is of course also partially due to the fact that the capping plate 207 is spring mounted and may thus move upwardly when it contacts with the cap and during the time that it is moving through the lower portion of its orbital path of travel.

Since the capping plate 207 is in the open atmosphere and hence will not be heated by steam from the steam chamber 18, the plate will remain at a normal temperature. As a result, contact of the plate with a cap C will immediately cause the steam within the head-space of a container to be condensed, thereby establishing a vacuum condition within the head space of the container.

The caps to be applied by the present machine may be of either the type wherein a head-space vacuum alone is relied upon to hold the cap seated and sealed, or the cap may be of the type wherein retaining means are provided upon the cap to hold the latter in sealed position or to assist a vacuum in holding the cap in sealed position.

A general description of the operation of the entire apparatus disclosed herein has been set forth in the opening portion of this specification, and the specific operation of each mechanism has been set forth in connection with the description of the construction of each mechanism.

It will be obvious that the various mechanisms comprising elements of the present apparatus may be used alone as well as in other apparatus.

The phraseology used in the specification is for the purpose of description and is not intended to limit the invention, the scope of the invention being indicated in the claims.

I claim:

1. A steam chamber for vacuumizing containers, said chamber having an inlet and an outlet therein through which conveying means may move, a steam inlet, and a reticulated element adjacent said steam inlet to break the force of the stream of steam issuing from said steam inlet to provide a quiet body of steam in the steam chamber.

2. A steam chamber for vacuumizing containers, said steam chamber being of box-like form and having an inlet and an outlet through which a container may move through the steam chamber, a reticulated element extending across the upper portion of said chamber and a steam inlet line on the opposite side of said element from the container inlet and outlet, said reticulated element serving to break the force of the steam issuing from said steam inlet line and provide a quiet body of steam in said steam chamber.

3. A steam chamber for vacuumizing containers, said steam chamber being of box-like form and having an inlet and an outlet through which a container may move through the steam chamber, a reticulated element along a portion of said chamber and a steam inlet line on the opposite side of said element from the container inlet and outlet, said reticulated element serving to break

the force of the steam issuing from said steam inlet line and provide a quiet body of steam in said steam chamber.

4. In combination, a steam chamber having an inlet and an outlet, a container supporting conveyor moving through the inlet and outlet of said chamber, a steam inlet, a reticulated element between said steam inlet and said conveyor and above the latter to break the force of the steam issuing from said steam inlet, the area defined between said steam inlet and said reticulated element including a portion extending laterally along said conveyor and toward the chamber outlet.

5. In a container vacuumizing apparatus, a steam chamber having an inlet and an outlet through which conveying means may move, a steam inlet, a reticulated element adjacent said steam inlet to break the force of the steam issuing from said steam inlet to provide a quiet body of steam in the steam chamber, and heating means independent of the steam delivery means to maintain the walls of the tunnel at high temperature.

6. In an apparatus for vacuumizing contain- 25

ers, a steam tunnel, means for conveying containers through said tunnel, steam delivery means including jetting means and baffle means so relatively disposed that the jets strike the baffle means, and a perforate wall disposed between the steam delivery means and the path of the containers in the tunnel, whereby a relatively quiet body of steam is provided in the path of the containers in said tunnel.

7. In a container vacuumizing apparatus, a tunnel adapted to enclose a container, means to move containers through the tunnel, means to deliver steam to the tunnel including a steam supply line, an expansion chamber of substantially greater cross-section than the supply line to receive steam from the latter, said expansion chamber including a screened outlet opening directly to the tunnel to break the force of the steam so that the steam will move into the tunnel at sufficiently low velocity to maintain a quiet cloud of steam in at least the upper portion of the tunnel to heat and replace air within the head space of a container, and means to apply and seal caps to the container.

ROBERT J. STEWART.
